J. P. SEAHOLM

LATCH LEVER

Filed Feb. 13, 1922

INVENTOR:
John P. Seaholm
L.C. Shantz Attest

UNITED STATES PATENT OFFICE.

JOHN P. SEAHOLM, OF MOLINE, ILLINOIS, ASSIGNOR, BY MESNE ASSIGNMENTS, TO
MOLINE PLOW COMPANY, INCORPORATED, OF MOLINE, ILLINOIS, A CORPORATION
OF VIRGINIA.

LATCH LEVER.

Application filed February 13, 1922. Serial No. 536,221.

To all whom it may concern:

Be it known that I, JOHN P. SEAHOLM, a citizen of the United States, residing at Moline, county of Rock Island, State of Illinois, have invented certain new and useful Improvements in Latch Levers, of which the following is a specification.

The invention relates to latch levers.

It is particularly concerned with levers used with agricultural implements.

It is always desirable and frequently necessary to have the handle of a latch lever in a position where it may be easily grasped by an operator seated on an implement, but it is very often impossible to have the handle of a straight lever positioned so that it may be easily grasped. The difficulty has been overcome by bending the lever, but this has always introduced the complication of having to provide some kind of a mechanism for transmitting the motion of the latch operating means past the bend in the lever. It has heretofore been customary to do this by providing a series of levers or other devices which are made in more than one piece and usually are somewhat complicated and expensive. The present invention has been devised to accomplish this object in a much more economical and efficient manner.

The general object of the invention is to provide an improved latch lever.

A more specific object is to provide a simple construction for transmitting the motion of the latching means of a bent lever past the bent portion of that lever.

Other objects and advantages of the invention will appear from the specification and drawings.

An embodiment of the invention is illustrated in the accompanying drawings, in which—

Figure 1 is a side elevation of the latch lever.

Figure 2 is an end elevation.

The lever comprises a bent body member 1, a latch member 2 mounted in a guide 3 and a link 4 operated by a latch handle 5.

The body member 1 is preferably bent from a single strip of flat metal and provided with a handle portion 6 and an opening 7, the latter being used to pivot the handle to the implement with which it is to be used. A slot 8 is formed slightly below the bent portion of the body to receive one end of the latch as will be hereinafter de-

scribed. This member can be easily stamped from a flat metal bar with the holes punched and the handle formed in one operation and it then can be subsequently bent to the desired shape.

The guide member 3 is likewise bent from a strip of flat metal into the shape shown in the drawings and is attached to the body member at the bent portion thereof by being riveted or otherwise attached. The guide has a hole 9 in the top lip thereof and a slot 10 in the bottom portion, both for the reception of the latch member 2. The slot 10 coincides with the slot 8 in the body member and is of substantially the same width and length. The hole 9 is slightly larger than the diameter of the latch member 2 in order that there may be a slight play between the parts.

The latch member 2 is bent from a round metal rod, one end being bent at right angles to form the locking portion 11, such portion projecting through the slots 10 and 8 and being kept from endwise movement by a cotter pin 12 or the like. The body of the latch member is bent to substantially the same angle as the body portion of the lever and the upper end projects through the hole 9 in the guide 3 as illustrated. Projections 13 are struck up from the body of the latch member and bearing against these and against the upper lip of the guide member, is a spring 14 which serves to normally bias the latch member downwardly into locking position.

The link 4 is connected to the upper end of the latch member and to the lower end of the pivoted handle 5, the latter being pivoted in any desired position on the body member 1, preferably near the upper end thereof adjacent the handle portion.

This construction is simple and inexpensive and, at the same time, durable and efficient. When the handle 5 is pressed toward the body 1 of the lever, the link 4 is pulled upwardly, which, in turn, pulls the latch member 2 upwardly against the tension of spring 14, thereby unlatching the lever. The latch member 2 slides through the openings 3, 10 and 8 without substantial friction due to the fact that the bend in the lever is a gradual one and due to the fact that the latch member has the same curvature as the body member so that the pull is efficiently transmitted.

This simple structure made of a few parts solves a problem that has been before implement manufacturers for a large number of years and which heretofore has always been thought impossible of practical solution except by mechanism including a larger number of parts involving more expense.

It is to be understood that the construction shown is for purposes of illustration only and that other structures may be devised without departing from the spirit and scope of the appended claims.

I claim:

- 15 1. A latch lever having a bent body member, a reciprocating latch member adjacent the bent portion of the body member and bent to substantially the same angle, and means for reciprocating the latch member.
- 20 2. A latch lever having a bent body member, a reciprocating latch member supported on said body member adjacent the bent portion thereof, said latch member being substantially parallel to the body member and being bent to substantially the same angle, and means on the body member for reciprocating the latch member.
- 25 3. A latch lever having a bent body member, a reciprocating latch member carried by the body member adjacent its bent portion, said latch member being bent to substantially the same angle as the body member, a guide for a latch member a spring normally biasing said latch member in one direction, and means carried by the body member for reciprocating the latch member in the other direction against the tension of the spring.
- 30 4. An angular latch lever having a bent body member made from a single strip of metal, a guide member bent from a single strip of metal and fixed to the body member at the bent portion thereof, a latch member mounted in the guide, said latch member being bent from a single strip to substantially the same angle as the body member, a spring for normally biasing the latch member in one direction, a link connected to the latch member, and a handle connected to the link and pivoted to the body member near the end thereof for manipulation of the latch member against the tension of the spring.

5. A latch lever having a bent body member, a reciprocating latch member located adjacent the bent portion of the body member and bent to substantially the same angle, one end of said latch member being guided so as to move substantially parallel to the axis of one portion of the body member, and the other end of the latch member being guided so as to move substantially parallel to the other portion of the body member, and means for reciprocating the latch member.

6. A latch lever having a body portion adapted to be pivoted to a frame and to co-operate with a toothed sector, a bend in the body portion above the point where it is adapted to co-operate with a toothed sector, a reciprocatable latch member carried by the body member and adapted to co-operate with a toothed sector, said latch member being bent to substantially the same angle as the body member and being located adjacent the bend in the latter, a guide for a latch member on one side of the bend in the body member, and a guide for a latch member on the other side of the bend, a spring normally biasing the latch member to engage a toothed sector, and means for moving the latch longitudinally against the action of the spring.

7. A latch lever comprising a body member adapted to be pivoted to a frame and to co-operate with a toothed sector, a bend in the body member above the point where it is adapted to co-operate with a toothed sector, a guide attached to the body member near its bent portion, one end of the guide being spaced from and substantially parallel to the body member to form a guide for a toothed sector, and the other end of the guide on the other side of the bend in the body member projected outwardly to form a guide for a latch member, a latch member having one end guided in the projecting end of the guide member and the other end bent and projected through slots in the guide member and the body member and adapted to co-operate with a toothed sector, and means for reciprocating the latch member.

In testimony whereof, I affix my signature.

JOHN P. SEAHOLM.
